UNITED STATES PATENT OFFICE.

VICTOR LEE EMERSON, OF PHILADELPHIA, PENNSYLVANIA.

APPARATUS FOR THE CONVERSION OF HYDROCARBON OIL.

Application filed June 25, 1921. Serial No. 480,418.

To all whom it may concern:

Be it known that I, VICTOR LEE EMERSON, a citizen of the United States, residing at Philadelphia, county of Philadelphia, and 5 State of Pennsylvania, have invented certain new and useful Improvements in Apparatus for the Conversion of Hydrocarbon Oil, of which the following is a specification.

10 This invention comprises improvements in apparatus for the conversion of hydrocarbon oils and the like and is herein disclosed in connection with apparatus of the type set forth in my Patent No. 1,367,806 February 8, 1921.

It is an object of my invention to provide means whereby, in the preliminary stages of operation, the oil to be treated is brought to the desired temperature in a rapid and efficient manner.

20 It is also an object of my invention to provide means which return to the thermo-cycle a large amount of heat which otherwise would be lost during the normal operation.

25 A further object is to provide a means by which a return of heat to the thermo-cycle is accomplished by the transmission of such heat to the fresh supply of oil while being supplied to the system under normal operation.

30 Another object consists in the provision of means by which liquids may be transferred to the different portions of the system with ease and facility.

35 Further objects will hereinafter appear in the description.

40 All these objects are accomplished in the apparatus herein disclosed which is a preferred form of an embodiment of my invention.

45 In the drawings Fig. 1 is a vertical elevation, partly in section of the apparatus composing part of the system.

Fig. 2 is a general plan view of the system and connected apparatus.

50 At 1, is shown a base receptacle and connected apparatus similar to the base receptacle disclosed in my patent above referred to. 2, indicates the supply of gaseous products from the secondary still. 3, indicates the impact apparatus with delivery of the products therefrom into the liquid in the receptacle 1, through the header 4.

55 At 5, is shown the lower portion of the condensing tower with delivery of a portion

of the condensates therefrom to the base receptacle through a conduit, as shown.

At 6, is shown a tunnel conducting the heated products of combustion from the furnace of the still 7, to the stack 8. Located in the tunnel 6, is a preheater 9. 10, is a conduit for the supply of fresh oil to be treated. The fresh oil is delivered to the preheater 9 from the conduit 10 at a point 11, near the bottom of the preheater, as shown. 12, is a conduit leading from the top of the preheater 9 and delivering into the base receptacle 1 at a distance from the bottom thereof, as shown. 13, is a steam operated pump having inlets 14 and 15, and outlets 16 and 17. A valve controlled conduit 18 connects the inlet 14 with the conduit 10 and a valve controlled conduit 19 connects the inlet 15 with the base receptacle 1 near the bottom thereof, as shown. A valve controlled conduit 20 connects the outlet 17 with the conduit 10 and a valve controlled conduit 21 connects the outlet 16 with the still 7. A valve controlled conduit 22 connects the conduit 10 with the base receptacle 1. Valves 23 and 24 are placed in the conduit 10 for the purposes hereinafter described.

It will be noted that the conduit 10 declines toward the rear of the preheater 9 and that the preheater 9 inclines toward the base receptacle 1. The position of the parts thus described aids in the production of the circulation by convection hereinafter described.

In the preliminary stages of operation the system is filled with oil to a desired level which, on account of the expansion of the oil, when heated is below the final operating level. The filling level thus described has been found to lie in a plane somewhat below the sight gauge 25, which indicates the level under normal operation.

The oil entering through the conduit 10 may be placed under pressure by means of a pump or by placing the source of oil at a level so as to cause a flow by gravity. During the filling operation the valves 23 and 24 and the valve in the conduit 22 will be open. Oil may thus pass into the receptacle 1 through the conduits 22, 10 and 12. At this time, the valve in the conduit 19 may be opened and the pump 13 actuated so as to draw oil from the base receptacle 1 and feed it into still 7 through the conduit 21 until the still is filled to the desired level which

will be lower than the level when in normal operation due to the expansion of the oil when heated. The level of the oil in the still 7 may be indicated by series of try cocks suitably positioned thereon.

With the parts in the position thus described combustion may be started in the furnace of the still 7. The products of combustion passing through the tunnel will pass over the preheater 9 and heat the oil therein. The valves in the conduits 18, 21 and 22, and valve 24 may now be closed and the pump 13 actuated so as to circulate the oil from the base receptacle 1 through the conduits 19, 20 and 10, preheater 9 and conduit 12 back to the base receptacle 1. At this time the valve in the conduit 20 is opened while during the preliminary filling it may be closed, if desired, if the outlet valve of the pump is not such as to form a positive check.

Another mode of circulation through the base receptacle 1 and preheater 9 may be accomplished when the oil in the base receptacle has expanded or risen above the inlet of the conduit 12 thereto by convection. When the circulation is accomplished in this manner the valve in the conduit 22 is opened and the heated oil in the preheater 9 rises through the conduit 12 and passes into the upper part of the base receptacle 1. Being lowered in temperature by heat interchange with the cooler oil therein a convection current is established through the conduits 22 and 10 back to the preheater 9 where the oil is again heated and returned to the base receptacle 1.

This circulation causes the oil in the base receptacle to be heated during the preliminary stage of operation which aids materially in rapidly bringing the system to normal operation. When the gaseous products in the still 7 reach the desired pressure they may be admitted through the conduit 2, jet apparatus 3 and header 4 into the oil in the base receptacle 1. This results in the rapid heating of the oil therein. At this time the valve in the conduit 21 may be opened and the oil from the base receptacle passed to the still 7. The valve in the conduit 20 may then be closed and the pump 13 caused to feed the oil from the base receptacle 1 to the still 7 in normal operation. The action of the pump 13 in normal operation is controlled automatically by an apparatus not shown responsive to the liquid level in the still 7 so as to keep the level therein constant. At this time the valve 23 may be opened and fresh oil fed to the system in accordance with the quantity demanded for normal operation by regulation of the valve 24. This oil becomes preheated by passing through the preheater 9 before entering the base receptacle 1 through the conduit 12.

On discontinuing the operation various

parts of the system may be drained by the apparatus herein provided. For this purpose the valves in the conduits 17 and 19 and valve 24 may be opened and valve 23 closed. The pump 13 is then operated to withdraw the liquid in the base receptacle 1 and force it back through the conduit 10 to the main supply or if desired by suitable conduit to a separate reservoir. When it is desired to withdraw the contents of the preheater 9 the valve 23 may be closed and the valve in the conduit 19 closed and the valve in the conduit 18 opened. The liquid in the preheater 9 will then be drawn through the conduits 10 and 18 by the pump 13 and forced back through the conduit 10 to the main supply or separate reservoir as described. The declining portion of the preheater 9 and the location of the end of the conduit which is at the point 11 near the bottom thereof permits a thorough withdrawal of the liquid in the preheater.

In the normal operation the base receptacle 1 acts as a primary still since the oil delivered thereto in a preheated condition is further heated by the heat interchange which takes place between it and the gaseous products issuing from the header 4. This results in the separation, in the gaseous form, from the oil thus introduced, those constituents which are vaporizable at the temperature at which the liquid in the base receptacle 1 is maintained. The gaseous products of this heat interchange pass to the condensing tower mounted on the base receptacle in which they are subjected to fractional condensation and a portion of the condensates returned to the base receptacle. The mixture of oil condensates, the latter being formed both by fractional condensation in the tower and upon contact of the gaseous products of distillation from the still 7 with the cooler oil in the base receptacle 1, are fed to the still 7 where they are further subjected to distillation under heat and pressure. The still 7 therefore acts as a secondary still with reference to the treatment of the original oil as carried out in the system.

In operation I have found that the apparatus herein disclosed greatly aids in an efficient and rapid operation of the system.

What I claim is:

1. in an apparatus of the class described, in combination, a still, a valve controlled conduit for supplying oil to said still, said still having a receptacle for the reception of said oil, a valve controlled conduit connecting said supply conduit with a lower portion of said receptacle, a preheater connected with said supply conduit, and a conduit connecting said preheater with the upper portion of said receptacle.

2. In an apparatus of the class described,

in combination, a still, a valve controlled conduit for supplying oil to said still, said still having a base receptacle for the reception of said oil, a preheater connected with said supply conduit, a conduit connecting said preheater with said receptacle, a pump connected with said receptacle and with said supply conduit adapted to circulate the oil from said receptacle through said preheater and conduits back to said receptacle.

3. In an apparatus of the class described, in combination, a primary still, a conduit for supplying oil to said primary still, said primary still having a base receptacle for the reception of said oil, a preheater connected with said supply conduit, a conduit connecting said preheater with said receptacle, a secondary still, and a pump connected with said receptacle and secondary still adapted to transfer the oil from said receptacle to said secondary still.

4. In an apparatus of the class described, in combination, a primary still, a secondary still, a conduit for supplying oil to said primary still, said primary still having a base receptacle for the reception of said oil, a preheater connected with said supply conduit, a conduit connecting said preheater and said receptacle, a pump having a plurality of outlets and inlets, a conduit connecting an inlet of said pump with said receptacle, a conduit connecting an outlet of said pump with said supply conduit and control valves in said conduits so arranged

as to permit said pump to transfer the oil in said receptacle to said secondary still and circulate oil from said receptacle to said preheater and back to said receptacle separately or simultaneously with the transfer of oil to said secondary still.

5. In an apparatus of the class described, in combination, a still, a conduit for supplying oil to said still, said still having a base receptacle for the reception of said oil, a preheater connected with said supply conduit, a conduit connecting said preheater with said receptacle, a conduit connecting said receptacle with an inlet of said pump, a conduit connecting an outlet of said pump with said supply conduit, a conduit connecting an inlet of said pump with said supply conduit and valves in said conduits so arranged as to permit said pump to circulate the oil in said receptacle to said preheater and back to said receptacle or withdraw the oil from said receptacle and preheater and eject it through said supply pipe.

In testimony whereof, I have signed my name to this specification in the presence of two subscribing witnesses, this fifteenth day of June 1921.

VICTOR LEE EMERSON.
